ICE CREAM VENDOR

William W. Hamel, Elizabeth, N. J., assignor to
Laham Corporation, Wilmington, Del., a corporation of Delaware

Application May 27, 1938, Serial No. 210,381

6 Claims. (Cl. 312—36)

This invention relates to improvements in ice cream vendors of the type refrigerated by solidified carbon dioxide and having a coin controlled delivery mechanism.

Its principal objects are to provide a simplified construction of such devices whereby their thermal characteristics are improved, and to provide a simple and effective mechanism for delivering packages one at a time from a plurality of packages stored within the apparatus.

Other objects will appear in the following specification in which an embodiment of the invention will be described and its novel features pointed out in appended claims.

Referring to the drawings,

Fig. 1 is a sectional side elevation of an ice cream vendor which is made according to and embodies the present invention. The section is taken on the line 1—1 of Fig. 2;

Fig. 2 is a sectional front elevation of the apparatus shown in Fig. 1, the section being taken on the irregular line 2—2 of the latter figure;

Fig. 3 is a sectional plan view of the same apparatus, the section being taken on the line 3—3 of Fig. 1;

Fig. 4 is a side elevation of a part of the device, showing the novel parts of its operating mechanism;

Figs. 5, 6 and 7 are plan views of three refrigerant supports of different thermal capacities, a desired one of which is selected for use for a known range of outside temperature condition.

In the drawings, 10 designates a metallic magazine for holding packages. It comprises a plurality of parallel plates 11 dividing it into compartments, A, B, C, D. 12 is the back of the magazine. 13 is a buffer space at the rear of the back 12. This space is closed at the top and bottom by blocks 15, 15, except for perforations 16 therein, which are provided for a purpose which will be pointed out later. A heavy metallic plate 17 lies over the top of the magazine 10 and extends downwardly for a short distance over its sides, as shown in Fig. 2.

The upper and lower parts of the front of the magazine are closed by metallic plates 18 and 19. A metallic door 20 is provided to give access to the interior of the magazine and to close the space between the plates 18, 19. The door 20 is hinged to the lower front plate 19 at 21 and can be swung down to the position in which it is indicated at 20A in Fig. 1 to form a service shelf. When closed it is in intimate contact with the front edges of the plates 11 and is held in its closed position by a latch 22. Thus, the maga-

zine when the door is shut, forms an all-metallic structure which is entirely closed except at the bottom.

The back and sides of the magazine are covered by bodies of insulation 30, 31, 31 outside of which are the back 40 and sides 41, 41 of a casing which encloses the whole apparatus. 32 is an insulation member which extends between the side bodies 31, 31 from the plate 18 to the front 10 of the casing. 33 is another insulation member between the sides 31, 31 extending from the plate 18 to the front of the casing.

32 is an insulating door in front of the magazine door 20. It is hinged at 24 and arranged to fit into shoulders 34, 35 on the insulation members 32, 33, respectively, and shoulders, 36, 36, 37, 37 on the side bodies 31, 31. Gaskets 38 are provided around the edges of the door against which the door is forced by a clamping device 25.

20 The back and sides 38, 31, 31 extend upwardly above the magazine 10 to form a refrigerant chamber 50, the bottom of which is formed by the plate 17 and a part of the insulation member 32. The plate extends forwardly from the magazine and its front edge is bent upwardly, as at 11A (Fig. 1). The top of the refrigerant chamber is formed by a body of insulation 51 over which is the top 42 of the casing. 52 is an insulating door, hinged at 53 for closing the front of the refrigerant chamber. It fits shoulders 54, 55 formed in the insulation member 32, shoulders 56, 57 formed in the body 51 and similar shoulders in the side bodies 31, 31. Gaskets 58 are provided against which the door may be forced by a suitable clamping device such as that shown at 25 in Fig. 3 for the door 23. 59 is a baffle plate spaced from the back body of insulation 30, extending upwardly from the plate 17 to a line near the top of the refrigerant chamber.

40 60 is the front of the casing, which is provided with a door 44 over its part which is in front of the doors 23 and 52 and extending somewhat below the lower door 23, for a purpose which will appear later.

45 60 is a cylindrical ejector of insulating material under the magazine 10, the plates 11 of which extend into grooves in the ejector. The ejector is affixed to a shaft 61 by means of which it is actuated. The periphery of the ejector is cut away to form segmental pockets 62 spaced 90° apart, each of which is aligned with one of the compartments of the magazine. Each of the pockets is formed with a shoulder 63. The uncut periphery of the ejector supports columns of 50 packages 64 of ice cream (in the specific embodiment

ment herein described), in the compartments of the magazine, sufficiently above the lower edge of the plate 19 to prevent their removal. When the ejector is rotated to bring one of the pockets 62 into register with its respective compartment, the column of packages in that particular compartment moves downwardly a sufficient amount to bring its lowermost package below the lower edge of plate 19. Further rotation of the ejector through 90° will cause the shoulder 63 of the pocket, into which one of the packages has dropped, to force this package forwardly out of the magazine and will bring another pocket 62 into alignment with another of the magazine compartments.

The ejector is within a space 65 surrounded by an inner casing into which the orifice in the lower block 15 opens. This inner casing has an inclined ledge 66 across the front of the ejector.

67 is a valve chamber through which the ejected package passes into a chute 70. The front of the valve chamber is formed by a body member 68 of insulation above and between the chute 70 and the front 43 of the casing and by a slide 69 between the insulation member 33 and the insulation body 68. This slide may be removed for inspection of the parts within the valve chamber. When closed it abuts a gasket.

The side of the chute directly below the valve chamber converges, as shown in Fig. 2, and form the sides of a delivery opening 71 in the front 43 of the casing. A flap 72 affixed to a shaft 73 lies over the delivery opening. It is adapted to be raised manually to the position indicated by dotted lines at 72A in Fig. 1 to give access to the interior of the chute. The passage through the chute is closed by an auxiliary flap 74 when the flap 72 is raised. This is effected by mechanism shown in Fig. 4. Auxiliary flap 74 is affixed to a shaft 75. Levers 76 and 77 are affixed to shafts 73, 75, respectively, and their outer ends are interconnected by a link 78. 79 is another lever affixed to shaft 73 for the purpose of locking the flaps during a desired part of the operation. A pin 103 projects laterally from one side of the free end of this lever 79.

80 is a valve in chamber 67 affixed to a shaft 81. It has a soft resilient end adapted to rest on the ledge 66 to form therewith a substantially air-tight closure. To further seal this joint a flap 82 or the like is affixed to the valve 80. This effectively closes the passage between the ejector chamber 65 and the valve chamber 67 when valve 80 is closed. The passage from the valve chamber 67 into chute 70 is similarly closed by a valve 83 on a shaft 84 which seats against a vertical wall of an inner casing which forms the ejector chamber 65. Valve 83 is provided preferably with a soft resilient edge. Shafts 81, 84 are interconnected by levers 85, 86 and link 87 shown in Fig. 4, and the valves are held seated by a weight 88 on a lever 89 affixed to shaft 84.

90 is a coin detector which releases an actuating lever 91 so arranged that when pulled down it will move a toothed rack 92 to the right, as viewed in Fig. 4. Details of this mechanism are not shown as they form no part of my invention.

A pinion 93 loosely mounted on the ejector shaft, meshes with the teeth on bar 92. It carries a pawl arm 94 and pawl 95 which engages a ratchet 96 fast on shaft 61 and imparts a quarter of a revolution to the ejector every time lever 91 is pulled down.

98 is an arm affixed to rack 92 and connected by a slotted link 99 with a pin on a lever 100 75

affixed to shaft 84. Another arm 101 affixed to rack 92 has an extension 102 which passes over the pin 103 which projects from lever 79 and has a return bar 104 alongside of lever 79, the upper surface of which is directly below the pin 103. This return bar terminates at a point just short of the path of travel of the pin.

The initial movement of the rack 92 moves the return bar 104 under the pin 103 and thereby locks shafts 73, 75 so that the flaps 72, 74 cannot be opened during further movement of the bar 92 or until it has been returned to its initial position by spring 105. It is to be noted that pawl 95 engages ratchet 96 and link 99 engages the pin on lever 100 after the initial movement of the rack 92 has locked the flaps 72, 74. Further movement of rack 92 rotates the ejector and simultaneously opens valves 80, 83 to allow an ejected package to pass through valve chamber 67 into chute 70 and to a position directly back of flap 72. The latter can be raised only after valves 80 and 83 are closed and when flap 72 is raised to open the discharge outlet, flap 74 is raised to close the passage through the chute. Thus, no air will pass up through the chute and the valve chamber to the refrigerated magazine and ejector chamber.

Refrigeration is effected by placing solidified carbon dioxide 110 in the refrigerant chamber 30 50. This is enclosed in a bag 111 which retards its evaporation and absorbs any oil which may be entrained in it. If the thermal conductivity of the magazine 10 and the plate 17 are so proportioned and designed that the temperature of the package compartments would be too low, a supporting plate 112 may be interposed between the bag 111 and the plate 17. This supporting plate has lugs 113 of the needed number, size and material to effect the needed rate of heat exchange to produce the desired temperature in the apparatus. In order to meet changing conditions such as those caused by different outside temperatures, a number of these supporting plates are provided for each vendor, such as those shown at 112A, 112B and 112C in Figs. 5, 6 and 7, having different numbers of spacing lugs. Similar results may be attained by varying the size of the lugs or the material of which they are made.

I have found it advantageous to make the sides and top of the refrigerant material of insulating material without a metallic lining, as such a lining acts as a thermal conductor and rapidly distributes the low temperature produced by the sublimation of the CO₂ to the insulation. The inner surfaces of the refrigeration chamber are, however, coated with an impermeable varnish, as I use an insulation material which does not require the permeation of CO₂ gas to prevent its deterioration and as I desire to use the gas for a different purpose.

The baffle plate 59 causes the heavier CO₂ gas to replace the air within the chamber which retards sublimation, and the gas flows over it and down through the buffer space 13 into the ejector chamber 65. It serves to cool both the magazine and the ejector. The restricted opening 16 between the buffer space and the ejector chamber prevents the too rapid escape of the gas and insures against a return flow of air into the buffer space. A further effect of having the ejector chamber filled with gas is that its escape is through the valve chamber and chute where it counteracts any undesired tendency of air to enter the apparatus through these channels.

The apparatus herein shown and described embodies my invention in a practical structure, but many structural modifications can be made within its spirit and scope, and I intend no limitations other than those imposed by the appended claims.

What I claim is:

1. An ice cream vendor comprising a vertical refrigerated magazine, an ejector below the magazine, a discharge chute below and at one side of the ejector, a valve chamber between the ejector and the upper end of the chute, a valve in said chamber arranged to close said valve chamber, and opening mechanism for actuating the ejector and the valve together. 10

2. An ice cream vendor comprising a vertical refrigerated magazine, an ejector below the magazine, a discharge chute below and at one side of the ejector, a passage between the ejector and the upper end of the chute, a valve between the magazine and the upper end of the chute, another valve in said passage spaced from the first mentioned valve, said valves being arranged to close said passage, and mechanism for actuating the ejector and said valves together. 20

3. An ice cream vendor comprising a vertical refrigerated magazine, an ejector below the magazine, a discharge chute below and at one side of the ejector, the lower end of said chute forming a delivery opening, a manually movable flap over the delivery opening, and a mechanism for locking the flap and thereafter actuating the ejector. 25

4. An ice cream vendor comprising a vertical refrigerated magazine, an ejector below the magazine, a discharge chute below and at one 30

side of the ejector, the lower end of said chute forming a delivery opening, a manually movable flap over the delivery opening, a passage between the ejector and the upper end of the chute, a valve between the magazine and the upper end of the chute arranged to close said passage, and mechanism for actuating the ejector and the valve together, said mechanism including means for locking the flap. 5

5. An ice cream vendor comprising a vertical refrigerated magazine, an ejector below the magazine, a discharge chute below and at one side of the ejector, the lower end of said chute forming a delivery opening, a manually movable flap over the delivery opening, an auxiliary flap in the chute arranged to be closed by the opening movement of the flap over the delivery opening, and a mechanism for locking the flaps and thereafter actuating the ejector. 15

6. An ice cream vendor comprising a vertical refrigerated magazine, an ejector below the magazine, a discharge chute below and at one side of the ejector, a passage between the ejector and the upper end of the chute, a valve between the magazine and the upper end of the chute, another valve in said passage spaced from the first mentioned valve, said valves being arranged to close said passage, the lower end of said chute forming a delivery opening, a manually movable flap over the delivery opening, an auxiliary flap in the chute arranged to be closed by the opening movement of the flap over the delivery opening, and a mechanism for locking the flaps and thereafter actuating the ejector and the valves. 25

WILLIAM W. HAMEL.
